UNITED STATES PATENT OFFICE.

HENRY S. DICKINSON, OF JERSEY CITY, NEW JERSEY.

CHIMNEY-CAP.

SPECIFICATION forming part of Letters Patent No. 310,391, dated January 6, 1885.

Application filed June 23, 1884. (No model.)

To all whom it may concern:

Be it known that I, HENRY S. DICKINSON, a citizen of the United States, residing in Jersey City, Hudson county, New Jersey, have 5 invented a certain new and useful Improvement in Chimney-Caps, of which I declare the following to be a full, clear, and exact description, so that any person skilled in the art or science to which it appertains can make, 10 construct, and use the same, reference being had to the accompanying drawings, which form part of this specification, and to the letters and figures of reference marked thereon.

The invention relates to chimney-caps, and 15 has for its object the prevention of back-drafts in heavy winds and the securing of a certain and unobstructed draft at all times. It consists of the arrangement hereinafter described and claimed, and is an improvement 20 upon the chimney-cap secured to me in Letters Patent of the United States No. 299,628, granted June 3, 1884.

The accompanying drawings represent my improved device. Figures 1 and 2 are sectional views on the lines 1 1 and 2 2.

Like letters of reference indicate like parts. A is the flue, that is fastened to the chimney-top in any suitable way, so as to form a continuation of the flue of the chimney. It 30 is surmounted by the cap B, which is pierced by the transverse tube C. The tube C is open at both ends—to wit, at a and b. It is horizontal. When the wind drives into the tube at either end, it has a clear course through the tube and out at the other end. This tube C is cut through along its roof or upper part, thereby forming the opening d, through which communication is had with the interior of the cap B. This opening d is the only opening from 35 the interior of the cap B into the tube C. With the arrangement so far provided the

products of combustion pass up through the flue, around the tube C, within the interior of the cap B, down through the opening d into the tube C, and out through the openings a 45 or b, or both; but when there is no wind the arrangement described somewhat obstructs the draft, and when the wind drives very fiercely into either the opening a or the opening b it is apt to drive the smoke up through 50 the opening d, and so down the flue. To obviate these difficulties I cut out the top of the cap B over the opening d and mount upon the opening e so formed the cap D, which may be any form of cap having side openings and a 55 sloping and projecting top to protect against rain in the usual way. This cap D and opening e furnish a second protected opening, through which the products of combustion may pass from the interior of the cap B, and 60 their mode of combination with the other parts of the entire improved chimney-cap insures an unobstructed draft when no wind is blowing, and a good draft when a heavy wind is driving directly through the tube C, for so much 65 of the wind in the latter case as is forced upward through the opening d will find a direct and ready exit through the opening e and cap D, incidentally increasing the draft in the chimney by suction.

What I claim as new, and desire to secure by Letters Patent, is—

As a new article of manufacture, a chimney-cap consisting of the cap B, having openings d and e, the transverse tube C, having 75 openings a and b, and the cap D, substantially as and for the purposes set forth.

HENRY S. DICKINSON.
